UNITED STATES PATENT OFFICE

2,478,764

ELECTRIC VALVE DEVICE

Hans Keller and Hans Blätter, Wettingen, and Werner Imobersteig, Baden, Switzerland, assignors to Aktiengesellschaft Brown, Boveri & Cie, Baden, Switzerland, a joint-stock company of Switzerland

Application October 22, 1945, Serial No. 623,794
In Switzerland November 13, 1944

3 Claims. (Cl. 315—261)

1

This invention relates to electric valve devices, such as ignitron devices having an anode and a mercury pool cathode, and it has particular relation to the energization of the ignition electrode or igniter. Such devices have been termed "mutators." However, for present purposes they will be referred to as ignitrons.

Care must be taken during the igniting of single anode ignitrons to establish the so-called cathode spot, either continuously by constant energization or cyclically by impulse control for that purpose. With continuous energization, precautions are necessary to avoid arc back as a result of the continuous ionization and vapor development during half-cycles when the anode is negative. Auxiliary series-current circuits are required with the prior impulse control systems to insure ignition during the desired periods that may be of fixed duration or of adjustable duration as varied by phase control of the impulses. All of these systems serve to complicate the apparatus and increase the energy required for the auxiliary devices.

Accordingly it is an object of this invention to provide improved arrangements for establishing the cathode spot of the ignitron.

Another object is to reduce the likelihood of arc back at the anode of ignitron type devices.

A further object is to cause direct current to flow at all times through the igniter of an ignitron at a value just sufficient to maintain the cathode spot after it is once established.

Other objects of the invention will, in part, be obvious and will in part appear hereinafter.

For a more complete understanding of the nature and scope of this invention reference can be had to the following detailed description taken with the drawing in which:

Figures 1 and 2 illustrate, diagrammatically, two preferred embodiments of the invention.

According to this invention, a direct current is passed continuously through the igniter, the current being of limited magnitude and just sufficient to maintain the ignited cathode spot in the immediate neighborhood of the igniter under normal or favorable operating conditions. A substantially continuous maintenance of the cathode spot is insured by the provision of mechanism or circuit arrangements for automatically increasing the voltage on the igniter electrode if the cathode spot is extinguished.

Referring now particularly to Figure 1 of the drawing it will be noted that the reference character 10 denotes an ignitron having an anode 11, a mercury cathode 12 and an igniter 13, the lat-

ter being of a semi-conducting or high resistance material. It will be understood that the anode 11 and cathode 12 are connected in a conventional work circuit (not shown).

5 In accordance with this invention the igniter 13 and cathode 12 are connected by conductors 14 and 15 to a source of direct current 16, such as the illustrated direct current generator of the commutator type. The generator 16 is driven by alternating current motor 17 which, as indicated, is energized from a suitable source of alternating current. Interposed in the conductor 14 is an inductor 18 and a resistor 19, the former serving to maintain substantially constant current flow to the igniter 13 and the latter serving to limit the current flow thereto.

The ignition impulses for application to the igniter 13 to render the ignitron 10 conducting are provided by an impulsing device, identified generally by numeral 22. This device includes a transformer having a primary winding 23 connected for energization to the alternating current source, and a secondary winding 24 which is connected through a rectifier 25 to charge a condenser 26. The condenser 26 discharges through a glow tube 27 and the igniter 13 when switch contacts 28 are closed by an armature 29 on energization of a winding 30 which is connected between the conductors 14 and 15, as shown.

30 In operation, assuming that the circuit to the motor 17 is energized with alternating current, the motor 17 drives the generator 16 and operating voltage is applied across the conductors 14 and 15. The winding 30 is energized and attracts armature 29 to close the contacts 28. In the meantime, condenser 26 has been charged through the rectifier 25 by the transformer 23, 24. The condenser 26 discharges through the glow tube 27 and over the contacts 28 to form the cathode spot on the igniter 13 and render the ignitron 10 conducting. As soon as it becomes conducting, the voltage between the conductors 14 and 15 drops to such value that it is insufficient to maintain the winding 30 energized to the extent necessary to hold contacts 28 closed. Accordingly, the contacts open and only the limited voltage from generator 16 is imposed on the igniter electrode 13.

If for any reason the cathode spot should become extinguished, the voltage across the conductors 14 and 15 rises and winding 30 is thereupon energized sufficiently to close contacts 28. The cycle as previously described as discharge of the condenser 26 is repeated to re-establish the cathode spot. After the cathode spot has been

formed, it is maintained by the current supplied by the generator 16. This current is relatively small as compared to the impulse current that is supplied by the discharge of the condenser 26 to produce the cathode spot.

The supplying of the igniter 13 with direct current, as described, has the advantage that the cathode 12 is enabled to yield a substantially higher cathode current. The amount of vapor that is produced is a fraction of that produced by the prior continuous excitation methods so that the performance of the ignitron 10 is not impaired. In this operation the igniter 13 can be used to fix the cathode spot.

If at first, during the initial breakdown of the ignitron 10, no cathode spot is produced, additional shocks or impulses will be applied through the glow tube 27 but only if the condenser 26 is charged so high that the breakdown voltage of the glow tube 27 is exceeded.

Instead of the generator 16, any other suitable source of direct current may be employed.

As shown in Figure 2, vibrating means 34 can be provided for producing the cathode spot. For example, the vibrating means 34 may be of the electromagnetic type energized from the alternating current source through a switch 35 to re-establish the cathode spot if it is inadvertently extinguished. Thereafter a current of 2 to 3 amperes from the generator 16 is sufficient to maintain the cathode spot. It will be noted that, when the vibrating means 34 is provided, the impulse producing means or shock device 22, shown in Figure 1, is unnecessary.

We claim:

1. The combination with a cathode pool type vapor electric valve having a resistance igniter for initiating conduction between the anode and cathode of the valve by the formation of a cathode spot, of a source of direct current, circuit means connecting said source of direct current to said igniter, means limiting the direct current flowing through the igniter to a value just sufficient to maintain the ignited cathode spot in the immediate neighborhood of the igniter, a condenser and a current source for charging the same constituting a current pulsing device for

both initially establishing the formation of the cathode spot and reestablishing the same upon an extinction thereof during operation of the valve, and switch means controlled in accordance with the impedance of said circuit means for temporarily connecting said condenser to said igniter to discharge through the same.

2. The combination with a cathode pool type vapor electric valve having a resistance igniter for initiating conduction between the anode and cathode elements, of a source of direct current, circuit means connecting said source between the igniter and cathode pool, means limiting the flow of direct current through the igniter to a value just sufficient to maintain the cathode spot in the vicinity of the igniter once it has been established, a condenser and a current source for charging the same constituting a pulsing device for initially establishing the cathode spot and for reestablishing the same upon any extinction thereof during the time that the valve is operating, switch means for connecting said condenser to said igniter to discharge through the same, and relay means energized upon extinction of the cathode spot for closing said switch means.

3. A system for igniting cathode pool type valves as defined in claim 2 wherein the energizing winding of said relay means is connected between said igniter and cathode pool.
